VIBRATOR

John Gustaf Mauritz Brodén, Malmö, Sweden,
assignor to Kockums Mekaniska Verkstads
Aktiebolag, Malmö, Sweden, a corporation of
Sweden

Application April 11, 1946, Serial No. 661,216
In Sweden April 28, 1945

8 Claims. (Cl. 116—142)

1

One object of the invention is to provide a vibrator for converting with high efficiency a direct current in a pressure medium, such as air or gas, into a pulsating current, the said vibrator consisting of an oscillating member, suitably of the diaphragm type, which is arranged between a chamber on the one side and one end of both an inlet and outlet passage for the pressure medium on the other side. The foremost condition which must be fulfilled for this purpose is that 10 the oscillating member after each opening and passing of a quantity of pressure medium from the inlet passage to the outlet passage, shall close this connection again effectively.

Another object is to provide a vibrator the oscillating member of which during the opening and closing of the said connection moves in resonance with the column of the pressure medium in the outlet passage.

A further object is to provide a self-controlled vibrator for signal apparatus which comprises a resonator or outlet passage which partly reflects and partly radiates the oscillation energy or transmits it in some other manner.

The invention is described herewith in the form of examples with reference to the accompanying drawings.

Fig. 1 of the drawing shows diagrammatically a longitudinal section through a vibrator according to the invention for a signal apparatus. Figs. 1a and 1b are diagrammatic views illustrating various parts and forces acting thereon during the assemblance of the vibrator. Fig. 1c is a sectional view to an enlarged scale of part of the vibrator. Fig. 1d is a sectional view taken on the line 1d—1d, Fig. 1c. Figs. 2 and 3 show variants for the fixing of the oscillating member.

Although the invention is herewith described in its application to signal apparatus, this must not be understood as a limitation of the invention's scope since the latter can be used wherever it is desired to convert a direct current in a pressure medium into a pulsating current.

The vibrator according to Fig. 1 comprises a casing 1 with a cover 2, both provided with a flange 3 and 4, respectively, said flanges being connected to each other by means of bolts 5. The inlet passage 6 and the outlet passage 7 are provided with screw threads 8 and 9 for the connection of an inlet tube for the compressed air and a horn or resonator 10 which communicates with the passage 7. The inlet passage 6 opens into an annular chamber 11 in the casing 1, the said chamber 11 surrounding the inner end of the outlet passage 7 which is formed by a tube 37

2

extending into the casing and having an annular edge 19.

The oscillating member consists of two discs or diaphragms 12 and 13 of which the disc 12 is circular and substantially unperforated, whereas the disc 13 is circular and provided with a large central hole so that it has the form of a ring. The ring 13 has a somewhat larger external diameter than the disc 12.

The flanges 3 and 4 each have an outer, 14 and 15, and an inner, 16 and 17, annular contact face or edge, of which the outer edges 14 and 15 are laid against one another when the flanges are tightened up, and the inner edges 16 and 17 clamp the ring 13 between them. Between the outer, 14, 15, and inner contact edges 16, 17, a gap 18 is formed serving the purpose when the bolts 5 are drawn up, of causing the flange 4 to bend in towards the gap 18, thereby causing the ring 13 to be subjected to forces directed radially outwards around its entire circumference. For this purpose the contact edges 14, 15 should be so constructed that they come into contact with each other before the contact edges 16, 17 clamp the ring 13 between them. This mode of action is more clearly illustrated in Fig. 1a which shows the flanges 3 and 4 at the moment the contact edges 14 and 15 come into contact with each other as a result of the action of the force F exerted by the bolts 5. Upon continued action of said force, the contact edge 17 will be moved towards edge 16. The flange 4 may then be regarded as a lever having its fulcrum at point P, and the end of the lever or edge 17 will move along a circular path as indicated by the arrow C. During this movement, the force f (Fig. 1b) which clamps the ring 13 between the edges 17 and 16, will consequently be directed slightly towards the left, as viewed in Figs. 1a and 1b, and may be regarded as the resultant of a vertical force f_v and a horizontal force f_h , the last-named force being directed radially outwards and acts upon the ring 13 just when said ring is being clamped between the edges 16 and 17.

The outlet passage 7 is constructed in such a manner that its contact edge 19 against the ring 13 lies in a plane which differs from another plane determined by the contact edge 16. In Fig. 1 the first plane lies below the latter one. In consequence of this, when the ring 13 is clamped between the cover and the casing, the ring 13 will lie with its inner peripheral portion pressed against the edge 19 of the outlet passage and will assume a certain curvature. Owing to the fact that the ring 13, on being clamped

in the casing, is subjected to forces, exerted radially outwards around its circumference as mentioned above, these forces will not reduce but will rather increase the contact pressure of the ring 13 against the edge 19 of the outlet passage. If on the contrary these forces were directed radially inwards, they would tend to bend the ring 13 downwards and accordingly to ease the contact pressure against the edge 19 which in certain cases might cause the contact to cease entirely whereby the vibrator would be placed out of operation. The method of clamping the ring 13 in the casing is therefore of some importance with respect to the functioning of the vibrator.

The disc 12 is inserted with a slight radial clearance in a recess 20 in the cover 2. Thus, it has a certain movement in its own plane. The depth of the recess 20 is such that the disc 12 in its mounted position presses against the inner annular edge portion of the ring 13, and by means of the same pressure at its circumference, it lies against the bottom of the circular recess 20. Between the discs 12 and 13 and the inner wall of the cover 2 an annular space 36 having a triangular cross-section will thus be formed. At the same time a closed chamber 21 will be formed between the cover 2 and the disc 12.

To facilitate the assembly of the cover 2 and discs 12 and 13 with the casing 1, the discs 12 and 13 are placed in recesses in the cover and screws 22 are screwed into the cover 2 around the circumference of the ring 13, the said screws holding the ring 13 in position by means of their heads without clamping the ring tight. The disc 12 is thereby also held in position although it possesses a certain axial movement. By this means the cover with the discs can easily be set in its correct position with respect to the casing and screwed up tight by the bolts 5. In the casing 1 recesses 23 are provided corresponding to the heads of the screws 22.

The chamber 21 may be entirely closed, but in order to prevent the occurrence of too high an internal pressure in the chamber which might render the starting of the vibrator difficult or even impossible in some cases, the chamber 21 may suitably be provided with a very small hole 24 which connects the chamber with the surrounding atmosphere and thus gradually reduces the internal pressure in the chamber. In Fig. 1 this hole 24 is arranged in an inner projection 25 which extends from the cover into the chamber and is provided on the outside with a bore 26 having a relatively large diameter. By means of this arrangement the entrance of dirt into the hole is prevented since the hole 24 is well protected. In place of the hole 24 a corresponding hole 27 may be formed in the disc 12 which connects the interior of the chamber 21 with the outlet passage 7.

In Fig. 1 the annular space 36 with the triangular cross-section between the discs 12 and 13 is in connection with the chamber 21 through the small gap between the circumference of the discs 12 and the wall of the cover and also through one or more recesses 28 in the contact face of the cover against the disc 12. In place of this connection the disc 12 may be provided with one or more holes 29 which directly connect the chamber with the annular space 36.

In Fig. 2 a variant of the method for fixing the discs 12 and 13 is shown. According to this method the contact edge of the casing against the ring 13 is replaced by a packing 30. The fig-

ure shows further how an annular passage 31 is arranged around the circumference of the ring 13 and how this passage 31 is connected with the atmosphere by another passage 32. This arrangement has for its object to secure a satisfactory seal between the casing and the ring 13 and, in the event of compressed air leaking out between these parts notwithstanding, to lead this compressed air out to the atmosphere and prevent the compressed air from finding its way into the chamber 21 through the annular space.

Fig. 3 shows a third method of fixing the ring 13 according to which the ring extends the whole way between the two flanges 3 and 4 the contact surfaces of which are flat. With this method of fixing the ring 13 is not subjected to either inwardly or outwardly directed radial forces around its circumference and therefore has a contact pressure against the edge of the outlet passage which is not affected by the method of fixing the ring.

The outlet passage 7 has a special form which is described more particularly in connection with the Figures 4 and 5.

The mode of operation of the vibrator is as follows:

It may be assumed that the holes 27 and 29 are not present in the disc 12. When a direct current of compressed air is admitted to the inlet passage 6 it is converted to a pulsating current owing to the fact that the air in the annular chamber 11 pressed the ring 13 and consequently the disc 12 downwards as viewed in the drawing and admits a certain quantity of air to the outlet passage 7. When the air enters the outlet passage 7 this air will also act upon the disc 12 which thereupon bends further downwards and opens a gap between the discs 12 and 13 so that the air also passes into the annular space 36 and flows on over the edge of the disc 12 and through the recesses 28 into the chamber 21. Owing to the increase of pressure in the chamber 21 and the internal stresses in the discs as well as the effect of the outlet passage 7, these forces will quickly overcome the air pressure on the upper side of the discs 12 and 13, which will move upwards and, lying in contact with one another, will close the connection between the inlet and outlet passages. A certain pressure has thus been set up in the chamber 21, which pressure, on the disappearance of the pressure wave from the inner portion of the outlet passage, will act as a tightening pressure against the disc 12. The air flowing out through the outlet passage will be set in oscillation owing to the form and length of the passage, and when a pressure is reflected at the open end of the outlet passage, an increase of pressure or a pressure surge will be produced at the inner end of the outlet passage, the said surge acting on the disc 12 which thereupon decreases its pressure against the disc 13. During this time the pressure in the chamber 11 exerts a constant force on the disc 13 and, when the pressure surge begins, the discs 12 and 13 will again be bent downwards and a fresh quantity of air will flow over from the inlet passage to the outlet passage and a fresh quantity of air will pass into the chamber 21 if air has leaked out from the chamber 21 or if the air surge in question is more powerful than the preceding one, that is to say, if the strength of sound is increasing, whereupon the operation described will be repeated. The direct current of compressed air is thus converted into a pulsating current in the outlet passage. At the same time

a part of the air flows out through the hole 24 from the chamber into the atmosphere. This loss is small however, on account of the small dimension of the hole 24 and as long as the vibrator is in operation the loss is replaced by fresh air which flows in between the discs 12, 13, round the disc 12 and through the recess 23. Without the hole 24, the chamber 21 would also be under pressure during the time in which the vibrator is not in use which might have the result that when it was desired to start the vibrator the pressure in the chamber 21 would be so great that the compressed air in the annular chamber 11 would not suffice to press down the discs 12, 13, and open the connection with the outlet passage, so that the vibrator would not be able to start. Generally speaking however, notwithstanding good sealing arrangements, there is some leakage which gradually reduces the pressure in the chamber 21. If therefore it is desired to start the vibrator immediately after it has been in use, this leakage may be insufficient and in order to be on the safe side an artificial leak is advantageously introduced in the form of the hole 24. In such cases the hole 24 may be replaced by the hole 27 which provides for a restricted communication between the chamber 21 and the outlet passage 7. Similarly the connection through the recess 23 and over the gap between the disc 12 and the cover 2 may be replaced by the hole 29 in the disc 12.

From the foregoing it will be seen that it is important that the air from the chamber 11 be not able to penetrate round the periphery of the disc 13 into the chamber 21. In order to prevent the air from the chamber 11 from penetrating between the discs 12 and 13 at the inner edge of the disc 13, when said discs are in the positions shown in the drawing, the inner peripheral portion of the disc 13 should slightly extend inside the contact edge 19.

What I claim is:

1. A vibrator comprising a casing, an inlet passage for the supply of fluid under pressure into said casing, a tube extending into said casing and having an annular edge at its inner end, said tube forming an outlet passage for said fluid, a sound amplifying member communicating with said outlet passage, a vibratory diaphragm ring supported at its outer periphery in an air-tight manner by said casing and bearing at its inner periphery against said annular edge, a vibratory diaphragm disc supported at its periphery by said casing and bearing against the inner periphery of said ring, said disc and said ring and said casing forming between them an annular space, said ring being located between said inlet passage and said annular space, a substantially closed chamber on one side of said disc in opposite relation to said space and said outlet passage, and an open communication between said space and said chamber, said ring and said disc being operative by the differential between the pressures prevailing on both sides thereof to force said ring out of contact with said annular edge and said disc out of contact with said ring, whereby to permit flow of fluid from said inlet passage to said outlet passage and into said space and said chamber, and to seat said disc on said ring and to seat said ring on said edge, whereby to prevent flow of fluid from said inlet passage and from said space to said outlet passage.

2. A vibrator comprising a casing, an inlet passage for the supply of fluid under pressure into said casing, a tube extending into said casing and

having an annular edge at its inner end, said tube forming an outlet passage for said fluid, a sound amplifying member communicating with said outlet passage, a vibratory diaphragm ring supported at its outer periphery in an air-tight manner by said casing and bearing at its inner periphery against said annular edge, a vibratory diaphragm disc supported at its periphery by said casing and bearing against the inner periphery of said ring, said disc and said ring and said casing forming between them an annular space being substantially triangular in cross-section, said ring being located between said inlet passage and said annular space, a substantially closed chamber on one side of said disc in opposite relation to said space and said outlet passage, and an open communication between said space and said chamber, said ring and said disc being operative by the differential between the pressures prevailing on both edges thereof to force said ring out of contact with said annular edge and said disc out of contact with said ring, whereby to permit flow of fluid from said inlet passage to said outlet passage and into said space and said chamber, and to seat said disc on said ring and to seat said ring on said edge, whereby to prevent flow of fluid from said inlet passage and from said space to said outlet passage.

3. A vibrator comprising a casing, an inlet passage for the supply of fluid under pressure into said casing, a tube extending into said casing and having an annular edge at its inner end, said tube forming an outlet passage for said fluid, a sound amplifying member communicating with said outlet passage, said casing comprising two parts, each part having an external flange, bolts securing said flanges to each other, said flanges having interengaging contact faces located outside said bolts and contact faces located inside said bolts, a vibratory diaphragm ring supported at its outer periphery between said last-named contact faces and bearing at its inner periphery against said annular edge, the distance between said first-named contact faces in a position of the casing parts with their flanges facing each other with untightened bolts being slightly smaller than the distance between said second-named contact faces less the thickness of said diaphragm ring, a vibratory diaphragm disc supported at its periphery by said casing and bearing against the inner periphery of said ring, said disc and said ring and said casing forming between them an annular space, said ring being located between said inlet passage and said annular space, a substantially closed chamber on one side of said disc in opposite relation to said space and said outlet passage, and an open communication between said space and said chamber, said ring and said disc being operative by the differential between the pressures prevailing on both sides thereof to force said ring out of contact with said annular edge and said disc out of contact with said ring, whereby to permit flow of fluid from said inlet passage to said outlet passage and into said space and said chamber, and to seat said disc on said ring and to seat said ring on said edge, whereby to prevent flow of fluid from said inlet passage and from said space to said outlet passage.

4. A vibrator comprising a casing, an inlet passage for the supply of fluid under pressure into said casing, a tube extending into said casing and having an annular edge at its inner end, said tube forming an outlet passage for said

fluid, a sound amplifying member communicating with said outlet passage, a vibratory diaphragm ring supported at its outer periphery in an air-tight manner by said casing and bearing at its inner periphery against said annular edge, said outer periphery being located in a plane different from a plane contacting said annular edge, a vibratory diaphragm disc supported at its periphery by said casing and bearing against the inner periphery of said ring, said disc and said ring and said casing forming between them an annular space, said ring being located between said inlet passage and said annular space, a substantially closed chamber on one side of said disc in opposite relation to said space and said outlet passage, and an open communication between said space and said chamber, said ring and said disc being operative by the differential between the pressures prevailing on both sides thereof to force said ring out of contact with said annular edge and said disc out of contact with said ring, whereby to permit flow of fluid from said inlet passage to said outlet passage and into said space and said chamber, and to seat said disc on said ring and to seat said ring on said edge, whereby to prevent flow of fluid from said inlet passage and from said space to said outlet passage.

5. A vibrator comprising a casing, an inlet passage for the supply of fluid under pressure into said casing, a tube extending into said casing and having an annular edge at its inner end, said tube forming an outlet passage for said fluid, a sound amplifying member communicating with said outlet passage, a vibratory diaphragm ring supported at its outer periphery in an air-tight manner by said casing and bearing at its inner periphery against said annular edge, a vibratory diaphragm disc supported at its periphery by said casing and bearing against the inner periphery of said ring, said disc and said ring and said casing forming between them an annular space, said ring being located between said inlet passage and said annular space, and a substantially closed chamber on one side of said disc in opposite relation to said space and said outlet passage, said casing having recesses near the periphery of said disc so as to provide for an open communication between said space and said chamber, said ring and said disc being operative by the differential between the pressures prevailing on both sides thereof to force said ring out of contact with said annular edge, and said disc out of contact with said ring, whereby to permit flow of fluid from said inlet passage to said outlet passage and into said space and said chamber, and to seat said disc on said ring and to seat said ring on said edge, whereby to prevent flow of fluid from said inlet passage and from said space to said outlet passage.

6. A vibrator comprising a casing, an inlet passage for the supply of fluid under pressure into said casing, a tube extending into said casing and having an annular edge at its inner end, said tube forming an outlet passage for said fluid, a sound amplifying member communicating with said outlet passage, a vibratory diaphragm ring supported at its outer periphery in an air-tight manner by said casing and bearing at its inner periphery against said annular edge, a vibratory diaphragm disc supported at its periphery by said casing and bearing against the inner periphery of said ring, said disc and said ring and said casing forming between them an annular space, said ring being located between said inlet

5 open communication between said space and said chamber, said ring and said disc being operative by the differential between the pressures prevailing on both sides thereof to force said ring out of contact with said annular edge and said disc out of contact with said ring, whereby to permit flow of fluid from said inlet passage to said outlet passage and into said space and said chamber, and to seat said disc on said ring and to seat said ring on said edge, whereby to prevent flow of fluid from said inlet passage and from said space to said outlet passage.

20 7. A vibrator comprising a casing, an inlet passage for the supply of fluid under pressure into said casing, a tube extending into said casing and having an annular edge at its inner end, said tube forming an outlet passage for said fluid, a sound amplifying member communicating with said outlet passage, a vibratory diaphragm ring supported at its outer periphery in an air-tight manner by said casing and bearing at its inner periphery against said annular edge, a vibratory diaphragm disc supported at its periphery by said casing and bearing against the inner periphery of said ring, said disc and said ring and said casing forming between them an annular space, said ring being located between said inlet passage and said annular space, a substantially closed chamber on one side of said disc in opposite relation to said space and said outlet passage, said disc having a restricted opening between said chamber and said outlet passage, and an open communication between said space and said chamber, said ring and said disc being operative by the differential between the pressures prevailing on both sides thereof to force said ring out of contact with said annular edge and said disc out of contact with said ring, whereby to permit flow of fluid from said inlet passage to said outlet passage and into said space and said chamber, and to seat said disc on said ring and to seat said ring on said edge, whereby to prevent flow of fluid from said inlet passage and from said space to said outlet passage.

25 8. A vibrator comprising a casing, an inlet passage for the supply of fluid under pressure into said casing, a tube extending into said casing and having an annular edge at its inner end, said tube forming an outlet passage for said fluid, a sound amplifying member communicating with said outlet passage, a vibratory diaphragm ring supported at its outer periphery in an air-tight manner by said casing and bearing at its inner periphery against said annular edge, a vibratory diaphragm disc supported at its periphery by said casing and bearing against the inner periphery of said ring, said disc and said ring and said casing forming between them an annular space, said ring being located between said inlet passage and said annular space, a substantially closed chamber on one side of said disc in opposite relation to said space and said outlet passage, said chamber having a restricted communication with the ambient air, and an open communication between said space and said chamber, said ring and said disc being operative by the differential between the pressures prevailing on both sides thereof to force said ring out of contact with said annular edge and said disc out of contact with said ring, whereby to permit flow of fluid from said inlet passage to said outlet pas-

sage and into said space and said chamber, and to seat said disc on said ring and to seat said ring on said edge, whereby to prevent flow of fluid from said inlet passage and from said space to said outlet passage.
